Filed Apr. 21, 1971, Ser. No. 136,154

Term of patent 14 years

Int. Cl. D24—02

U.S. Cl. D83—1 F

FIG. 1 is a front perspective view of a fluid delivery apparatus embodying my new design;

FIG. 2 is a left side elevational view of the apparatus shown in FIG. 1;

FIG. 3 is a rear elevational view of the apparatus shown in FIG. 1;

FIG. 4 is a bottom plan view of the apparatus shown in FIG. 3; and

FIG. 5 is a rear perspective view of another embodiment of a fluid delivery apparatus embodying my new design.

The clamp structure shown in the embodiment of FIG. 5 has been omitted from FIGS. 2-4 for ease of illustration.

I claim:

The ornamental design for a fluid delivery apparatus, as shown and described.
